UNITED STATES PATENT OFFICE.

PETER KLINKHAMMER, OF LOS ANGELES, CALIFORNIA.

NECKTIE HOLDER.

1,423,498.

Specification of Letters Patent. Patented July 18, 1922.

Application filed December 3, 1921. Serial No. 519,722.

To all whom it may concern:

Be it known that I, PETER KLINKHAMMER, a citizen of the United States, residing at Los Angeles, in the county of Los Angeles and State of California, have invented new and useful Improvements in Necktie Holders, of which the following is a specification.

My invention relates to necktie holders, and a purpose of my invention is to provide an extremely simple, inexpensive and efficient holder adapted for securing the knot of a four-in-hand cravat in affronting relation with respect to a collar button and in such manner that the knot will occupy its proper position between the ends of a collar.

I will describe one form of necktie holder embodying my invention and will then point out the novel features thereof in claim.

In the accompanying drawings, Figure 1 is a view showing in front elevation a collar and cravat having applied thereto one form of holder embodying my invention.

Fig. 2 is a vertical sectional view taken on the line 2—2 of Fig. 1.

Fig. 3 is an enlarged detail view showing in front elevation the holder shown in the preceding views.

Fig. 4 is an enlarged detail view showing the holder in side elevation.

Referring specifically to the drawings in which similar reference characters refer to similar parts, my invention, in its present embodiment, comprises a holder constructed from a single length of resilient wire bent to provide at a point medially of its ends a yoke 15, the ends of which are slightly bent inwardly at 16 to provide a restricted mouth or entrance to the yoke, as is clearly shown in Fig. 3. The ends of the yoke are extended to provide divergent portions 17 which terminate in laterally and upwardly bent hooks 18 having terminals sharpened to provide prongs or penetrating portions 19.

In the applied position of the holder as shown in Figs. 1 and 2, the yoke 15 is adapt-

ed to embrace the shank of a collar button so as to lie contiguous to the head thereof, the restricted mouth of the yoke being of 50 such an area as to necessitate a slight expansion of the yoke ends when the yoke is applied to the button. This obviously provides the necessary securing means for retaining the holder as a unit upon the collar 55 button. With the yoke applied to the collar button as just described, the divergent portions 17 depend from the collar button in the manner clearly shown in Fig. 2 so that the hooks 18 extend outwardly from the shirt 60 and with the prongs spaced from the shirt and extending upwardly.

In using the holder, it is applied to the collar button subsequent to the tying of the cravat, and the hooks may be caused to penetrate the knot of the cravat by first lifting the knot, applying the holder to the collar button as previously described, and finally lowering the knot and forcing it against the holder so that the prongs penetrate the knot. 70 The holder is thus caused to retain the knot of the cravat in affronting relation with respect to the collar button so that sagging of the cravat knot is positively prevented and the tie at all times maintained in its proper 75 relation to the ends of the collar.

I claim as my invention:

A necktie holder formed from a single length of resilient wire bent to provide a yoke adapted to embrace the shank of a collar button, said yoke having a restricted mouth, linear portions extending from the ends of the yoke and arranged in divergent relation with respect to each other, and hooks having upwardly extending prongs 85 formed on the terminals of said portions and terminating at points below said mouth, said prongs being arranged in a plane disposed at an angle with respect to the plane of the linear portions. 90

In testimony whereof I have signed my name to this specification.

PETER KLINKHAMMER.
